THIRD WHEEL FRAME FOR HAND TRUCK

Carey Carpenter, P.O. Box 456, La Mesa, Calif.

Filed Aug. 7, 1964, Ser. No. 81,201

Term of patent 14 years

(Cl. D14—3)

FIG-5

FIG-4

FIG-3

FIG-6

FIGURE 1 is a perspective view of a third wheel frame for a hand truck, comprising my new design;

FIGURE 2 is a rear elevational view of the third wheel frame;

FIGURE 3 is a side elevational view of the third wheel frame;

FIGURE 4 is a front elevational view of the third wheel frame;

FIGURE 5 is a top view of the third wheel frame; and

FIGURE 6 is a bottom view of the third wheel frame.

The hand truck shown in broken lines is included for illustrative purposes only.

I claim:

The ornamental design for a third wheel frame for hand truck, as shown and described.
